UNITED STATES PATENT OFFICE.

GASTON BROWN KILLAM, OF EDMONTON, ALBERTA, CANADA.

GAS BURNER.

Application filed December 18, 1923. Serial No. 681,418.

This invention relates to improvements in gas burners, and the objects of the invention are to provide a simply constructed and economical device of this kind so constructed that the several parts will more efficiently perform the various functions required of them, and in which a considerable saving of gas will be effected without in any way curtailing the satisfactory results obtained.

With the foregoing and other objects in view the invention consists essentially of the novel arrangement and construction of parts as described in the present specification and illustrated by the accompanying drawings that form part of the same.

Referring now to the drawings in which like characters of reference indicate corresponding parts in each figure:

20 Figure 1 is a perspective view of an embodiment of my device.

Figure 2 is a longitudinal section.

25 Figure 3 is a section on line 3—3 of Figure 2.

In the drawings A designates an embodiment of my device as a whole, the essential features of which are a box or casing 10 provided with a suitable opening 11 with burner ring 12. Into the opening 11 is de-

30 signed to fit a conical-shaped spreader 13 adapted to be raised or lowered to allow the mixture of air from either one or both supply pipes to spread flame having integral therewith a stem portion 14 and suitable

35 supporting means thereon 15. The box 10 is divided substantially midway of its length by a suitable partition 16 designed to register with the opening 11 so that the box is evenly divided into two compartments to enable only one supply to be used as required.

40 17 and 18 are gas supply pipes communicating with the box 10 as illustrated, both these pipes being provided with mixing chambers 19 and 20 into which the gas is

delivered by the restricted pipes 21 and 22. The pipes 17 and 18 are also provided with sleeves 23 and 24 slidably mounted thereon and designed to regulate the admission of the additional air to the burner.

To regulate the spreader 13 I provide a cam-shaped member 25 pivotally mounted within the box 10 and designed to contact with the stem 14. The cam-shaped member is formed with an integral arm 26 extending beneath the box and pivotally connected at 27 to an operating rod 28 suitably supported by a bracket 29 on one of the mixing chambers and whereby, on the rod being moved inwardly, the stem 14 of the spreader is allowed to drop, into the aperture 11, and whereby, on the rod being drawn forward, the stem is shoved upwardly thereby opening the aperture 11 in the top of the box.

From the foregoing it will be seen that the flow of the mixture of gas and air through the supply pipes 17 and 18 to the burner can be simply and adequately controlled.

As many changes could be made in the above construction and many apparently widely different embodiments of my invention, within the scope of the claim, constructed without departing from the scope or spirit thereof, it is intended that all matter contained in the accompanying specification and drawings shall be interpreted in an illustrative and not in a limiting sense.

What I claim as my invention is:

A burner box having a circular opening in the top, a vertical partition in the box substantially midway thereof and contacting the top at the opening, a flame spreader provided with a stem mounted slidably on the partition and adapted to fit into the annular opening, and means for raising and lowering said stem.

In witness whereof I have hereunto set my hand.

GASTON BROWN KILLAM.
